EX

DESIGN.

—o—
L. P. BOWEN.
BICYCLE STAND.

No. 25,674.

Patented June 23, 1896.

UNITED STATES PATENT OFFICE.

LEANDER P. BOWEN, OF AUBURN, NEW YORK.

DESIGN FOR A BICYCLE-STAND.

SPECIFICATION forming part of Design No. 25,674, dated June 23, 1896.

Application filed April 22, 1896. Serial No. 588,643. Term of patent 7 years.

To all whom it may concern:

Be it known that I, LEANDER P. BOWEN, of Auburn, in the county of Cayuga, in the State of New York, have invented a new and useful 5 Design for Bicycle-Stands, of which the following, taken in connection with the accompanying drawings, is a full, clear, and exact description.

Figure 1 is an isometrical elevation of the o stand complete. Fig. 2 is a longitudinal vertical section through the recesses in the end pieces, these two views being deemed necessary to fully illustrate my design.

The leading feature of my design comprises 5 end pieces, connected by horizontal bars, the lower edges of said end pieces being cut away upon their adjacent edges, as shown in Fig. 2.

a are the ends or base-pieces, having a recess *b* upon their upper edge centrally, the lower edges of the pieces being cut away, as 20 shown at *c* at Fig. 2. *d* are the rods, substantially parallel, connecting the bases. The whole when complete forms a unique design and presents a pleasing effect to the eye.

What I claim as my invention, and desire 25 to secure by Letters Patent, is—

The design for a bicycle-stand substantially as herein described and shown.

In witness whereof I have hereunto set my hand this 13th day of April, 1896.

LEANDER P. BOWEN.

In presence of—

HOWARD P. DENISON,
MAUDE E. COOKE.
